COIN-CONTROLLED DISPENSING MACHINE

Jerome V. Kelly, Detroit, Mich.

Application January 18, 1947, Serial No. 722,823

4 Claims. (Cl. 312—35)

1

The present invention relates to a coin controlled dispensing machine particularly designed for dispensing articles which are enclosed within a sack or similar container.

It is the general object of the present invention to provide, in a machine of the type described, an improved and simplified means for supporting and serially releasing a plurality of articles, which means is characterized by the fact that each article is supported independently of the others and is free from the effect of the weight of the others.

Another object of the invention is to provide a machine of the type described adapted to contain two or more separate groups of articles and having a simplified manually operated means for selectively discharging an article from any desired group.

Another object of the present invention is to provide improved means for preventing improper operation of the machine.

Other objects and advantages of the invention will become apparent from the following specification, the accompanying drawings and the appended claims.

In the drawings:

Figure 1 is a front elevation of the machine with parts broken away to show a portion of the interior;

Figure 2 is a longitudinal section taken on the line 2—2 of Figure 1;

Figure 3 is a transverse section taken on the line 3—3 of Figure 2;

Figure 4 is a transverse section taken on the line 4—4 of Figure 2;

Figure 5 is an enlarged longitudinal section taken on the line 5—5 of Figure 4;

Figure 6 is an enlarged fragmentary longitudinal section showing the portion of the mechanism enclosed within the dotted line circle 6 in Figure 2;

Figure 7 is a development in section of the latching mechanism taken on the curved line 7—7 of Figure 3;

Figure 8 is a sectional view taken on the line 8—8 of Figure 1 in partly diagrammatic form, showing the coin handling mechanism; and

Figure 9 is a wiring diagram of the machine.

In coin controlled dispensing machines, it is necessary to provide storage for a relatively large number of articles of the same kind in order to reduce the need for frequent recharging of the machine. In some cases, either due to the weight or the fragile character of the articles dispensed by the machine, it is undesirable to stack the articles one on top of another. If the articles are fragile, such stacking may result in a crush-

2

ing of the articles; if the articles are of substantial weight, it may also make it difficult to withdraw an article from the bottom of the stack. These difficulties are overcome, in accordance with the present invention, by suspending the articles in an envelope or sack from a horizontally disposed cantilever screw. Thus, the screw not only acts as the support for the complete charge of articles of the same type, but, upon rotation in a step-by-step manner, discharges the articles one at a time. Since each article hangs freely in its sack or envelope, there is no danger of injury to the article and no interference with the discharge of articles from the end of the screw.

While the principle embodied in the present invention may be employed to dispense any type of article which may be enclosed within a sack or envelope, it has peculiar advantage in dispensing phonograph records which are positioned within the usual paper envelopes and, accordingly, the embodiment of the invention selected for illustration comprises a machine adapted to dispense disk phonograph records.

The machine in general comprises a casing 1 of any suitable material, such as sheet metal, within which is positioned a plurality of laterally opposed pairs of vertical supporting posts 2, 3, 4, 5 and 6. Positioned upon the upper ends of each pair of posts is a housing; thus, the posts 2 carry housing 7, the posts 3 carry housing 8, the posts 4 carry housing 9, the posts 5 carry housing 10 and the posts 6 carry housing 11. Each of the housings 7 to 11 supports and journals an article supporting and discharging feed screw 12 to 16, respectively. In the manner best shown in Figures 4 and 5 in connection with the housing 9, the feed screw 14 supports a plurality of phonograph records, which records are positioned within envelopes 18. The top portions of the envelopes are provided with apertures 19 of sufficient size to thread over the screw 14. The thread on the screw may be of any desired form but is preferably relatively deep and has a rounded root portion, as best shown in Figure 5. Screw 14 has a shank portion 20 which is journaled by means of antifriction bearings 21 carried by the housing 9, and a gear 22 is fixed to the shank 20 and positioned within the housing. Gear 22 meshes with a gear 23 to which is fixed at one side a faceplate 24 which carries one hub of the gear and which closes the countersunk opening 25 formed in the gear. The composite gear made up of the gear element 23 proper and the plate 24 is also journaled by means of antifriction bearings 26 in the housing 9. A circular disk 27 is positioned within the countersunk opening 25 and is provided with a central opening in which

is formed a plurality of helically splined teeth adapted to fit the helically splined shaft 28 which projects through the disk 27 and also through the composite gear 23-24. The opening formed in the gear 23-24 is of larger diameter than the outside diameter of the splined member 28, with the result that no direct contact occurs between the splined shaft and the gear. However, the disk 27 is provided with hub portions which are journaled within the gear opening and which serve to hold the splined shaft 28 on the axis of the gear.

The splined shaft 28 is connected at one end to a rod 29 which extends toward the front face of the machine and through a supporting and guiding plate 30, in the manner best shown in Figure 6. The forward end of the rod 29 is connected by means of a pin 31 to a square rod 32, the forward end of which projects through the front wall 33 of the casing 1 and carries a pull knob 34. The rods 29 and 32 and associated splined shaft 28 are normally held in their inward position by means of a coil spring 35 which bears at one end on the plate 30 and at the other end on the flange 36 of a sleeve 37 positioned on the rod 29. The forward end of the sleeve 37 limits forward motion of the rod 29 by engaging plate 30.

As a result of the above described arrangement, when the knob 34 is pulled outwardly, the splined shaft 28 is reciprocated axially without rotation, thereby causing a rotation of the splined disk 27. As best shown in Figure 4, the splined disk 27 is provided with a leaf spring 38 which extends tangentially with respect to the disk and is adapted to engage a ratchet tooth 39 which projects inwardly from the cylindrical wall of the countersunk opening 25. As a result of this construction, when the disk 27 is rotated counterclockwise, as viewed in Figure 4, incident to pulling of the knob 34 outwardly, the leaf spring 38 will drive the gear 23 in a counterclockwise direction. Since the gears 23 and 22 are of the same size in the illustrated embodiment of the invention and the screw 14 is a single thread screw, the pitch of the helix on the shaft 28 and the permissible outward movement of the knob 34 are such as to effect one revolution of the gear 23 and hence of the screw 14 when the knob is pulled outwardly to the full extent. When the knob is released and the splined shaft 28 returned by means of spring 35, the disk 27 will rotate in a clockwise direction without driving the gear 23, due to the one-way driving connection between the leaf spring 38 and the ratchet tooth 39.

As a result of this arrangement, screw 14 will be rotated one revolution on each operation of the knob 34. It will be appreciated that, if desired, a double or triple thread screw may be substituted for the screw 14 and appropriate changes made in the gear ratios and spline angle to advance the envelopes 18 the distance between successive threads on the screw for each operation of the knob 34 without departing from the principles of the invention.

In order to assist in holding the gear 23 against rotation on clockwise rotation of the disk 27, the face of the gear is preferably provided with a spherical recess 40 adapted to receive a spring-pressed ball 41 positioned within a suitable opening 42 formed in the wall of the housing 9. The position of the recess 40 is such that the ball enters the recess when the knob 34 is in its fully retracted position, illustrated in Figure 6, and the remaining parts are in the positions illustrated

in Figures 4 and 5. As a result, a full outward pulling movement of the knob 34 will rotate the gear 23 one complete revolution and allow the ball to re-enter the recess 40, with the result that it will assist in preventing reverse rotation of the gear on return of the knob to its retracted position.

As best shown in Figure 2, the screw 14, like the similar screws 12, 13, 15 and 16, is supported only at its rearward end, with the result that on each revolution it feeds all of the envelopes supported thereon to the right, dropping one envelope off the right-hand end on each complete revolution. The envelopes which are discharged from the ends of the screws drop upon a belt 63 which is supported on pulleys 44 and 45 located in the lower portion of the machine. The pulley 45 is adapted to be driven in any suitable manner by an electric motor 46. When the motor is operated, the belt moves in the direction of the arrow in Figure 2 and carries the discharged envelope to the right through a discharge opening 47 in the front wall 33 of the machine. A stop member 48, provided with a pair of upstanding fingers 49, operates to stop the outward movement of the envelope, even though the belt continues to move. At the point at which the envelope is stopped by the fingers 49, it may be grasped and withdrawn from the machine by hand.

The remaining feed screws 12, 13, 15 and 16 are identical in construction and mode of operation to the previously described screw 14 and are operated by similar mechanisms. The only difference between the housings 7, 8, 9, 10 and 11 resides in the fact that they are displaced angularly about the common axis of the screws 12 to 16, in the manner best shown in Figure 4, with the result that the axes of the pull rods are circumferentially spaced about the common axis of the screws. Thus, as best shown in Figure 4, the rearmost housing 11 is angularly displaced in a clockwise direction with respect to the housing 9 and contains a drive gear 50 which meshes with a gear 51 fixed to the feed screw 16. The drive gear 50 is operated by a pull rod 52 in the same manner as the gear 23 is operated by the rod 29. Housing 10 similarly contains a drive gear 53 which is operated by a pull rod 54, and the gear 53 meshes with a gear 55 on the screw 15. The housings 7 and 8 are displaced angularly in a counterclockwise direction with respect to the housing 9, and contain similar screw driving gears and associated parts.

The forward ends of all of the pull rods carry square rods similar to the square rod 32 associated with pull rod 29. Thus, a square rod 56 is fixed to the end of pull rod 52, a square rod 57 is fixed to the end of rod 54, a square rod 58 is fixed to the end of the rod (not shown) which operates screw 13, and a square rod 59 is fixed to the end of the rod (not shown) which operates screw 12. All five of the rods project through the forward end of the machine and carry pull knobs 60, 61, 62 and 63, respectively, with the result that an article may be discharged from any desired screw by pulling the appropriate knob.

Means are provided for latching all of the square rods 56, 57, 32, 58 and 59 in their inward positions, illustrated in the drawings, and for releasing the rods upon the deposit of an appropriate coin or coins. This means includes a pivoted latch associated with each of the rods. Thus, as shown in Figure 6, a supporting plate 64 positioned within the casing of the machine pivotally supports a latch 65 which is adapted to engage

within a notch 66 formed in the upper side of the square rod 32. Similar latches 67, 68, 69 and 70, all pivoted on the plate 64, engage, respectively, in similar notches in the square rods 56, 57, 58 and 59, in the manner best shown in dotted lines in Figure 3. Each of the latches is preferably provided with a spring for holding it in latched position, suitable springs for this purpose being indicated at 71, 72, 73, 74 and 75. While the latch 65 is pivoted solely on the plate 64, it will be noted from Figure 6 that the remaining latches are spaced rearwardly of latch 65 and hence are pivoted on pins which extend between the plate 64 and the plate 30. Suitable spacing sleeves are provided on the pins on either side of the latches, as best indicated in connection with the latch 67 in Figure 6. As there shown, the latch 67 is pivoted on a pin 76 which extends between the plates 30 and 64, and the latch is held in proper position along the pin by means of a pair of sleeves 77 and 78.

All five of the latches are adapted to be disengaged simultaneously upon energization of a solenoid 79 which is provided with a movable armature 80 that is connected to each of the latches by a separate flexible cable, the respective cables being trained over suitable pulleys journaled on pins carried between the plates 30 and 64. Thus, as best shown in Figures 3 and 6, the armature 80 is connected by means of a cable 81 to the latch 67, the cable 81 being trained over pulleys 82, 83 and 84. The pulley 82 is one of a plurality of pulleys journaled on a pin 85. Latch 68 is operated by a cable 86 which is trained over pulleys 87 and 88, the pulley 87 being journaled on the pin 85 and the pulley 88 being journaled on a pin 90 which carries the previously mentioned pulley 83. A flexible cable 91 connects the armature 80 to the latch 65, and cables 92 and 93 connect the armature to the latches 69 and 70. The cables 92 and 93 are trained over pulleys similar to those provided for the cables 81 and 86. As a result of this construction, energization of the solenoid 79 disengages all five of the latches from the square rods and de-energization of the solenoid permits return movement of the latches under the influence of the latch operating springs.

Means are provided to prevent more than one of the pull knobs 60, 61, 34, 62 and 63 from being pulled outwardly at one time. This means comprises a pivoted latch plate 94 carried between a plate 95 and the previously mentioned plate 64 on a pin 96. As best shown in Figure 3, the plate 94 is provided with five notches 97, 98, 99, 100 and 101 adapted to co-operate, respectively, with specially formed notches 102, 103, 104, 105 and 106 in the underside of the square rods 56, 57, 32, 58 and 59. As best shown in the developed sectional view of Figure 7, the notches in the latch plate and the square rods are so arranged as to permit withdrawal of only one of the square rods at a time. This result is achieved by beveling the rear edges of the slots 97, 98, 99, 100 and 101 in the plate 94 to form cam surfaces adapted to co-operate with similarly beveled surfaces formed in the rod notches to effect a shift of the latch plate when one of the rods is pulled in a direction to align the notch in the plate with the rod, such alignment being necessary by reason of the fact that the width of the notches in the plate is equal to the width of the square rods. Thus, as shown in Figure 7 in connection with the square rod 32, the notches in the square rod are provided with beveled cam surfaces 107 and 108 adapted to co-operate with beveled sur-

faces 109 and 110 on the rear edges of the notch 99.

When the parts are in the position illustrated in Figure 7, the notch 99 is aligned with the rod 32 and, consequently, rod 32 may be pulled outwardly without affecting any movement of the latch plate. However, it will be noted that the notches 97, 98, 100 and 101 are out of alignment with their associated rods 56, 57, 58 and 59. Accordingly, none of the rods may be pulled outwardly except the rod 32. If, however, it is desired to pull the rod 56, the beveled cam surface 110 on the rod notch will engage the beveled surface 111 on the rear edge of the notch 97 and swing the latch plate in a counterclockwise direction about the pin 96 until the notch 97 aligns with the rod 56. This movement of the latch plate will place all of the remaining notches out of alignment with their associated rods. The mechanism operates similarly when any of the other rod is pulled outwardly, with the result that in no case can two rods be pulled at the same time, even though all of the solenoid operated latches are released.

An important feature of the above described means for preventing movement of more than one of the rods at a time resides in the fact that the interlocking latch plate 94 is pivoted and hence may operate relatively freely. To facilitate such pivotal action, the latch plate 94 is preferably spaced slightly from the plate 95, as shown in Figure 6, and is so constructed that it will not deflect sufficiently to engage the plate 95 except upon application of a force greater than that necessary to swing it about its pivot pin 96.

The operation of the machine is controlled by a coin mechanism and an electric circuit, which are illustrated diagrammatically in Figures 8 and 9. The electric circuit, in turn, is controlled by two sets of switches, one of the switches of one set being operated when one of the control handles is pulled outwardly to its full extent. The switches of the other set operate to return the coins deposited in the machine when a knob is pulled and the associated article supporting screw is empty. The switches of the first set are conventional limit switches mechanically associated with the square bars 56, 57, 32, 58 and 59. Thus, as best shown in Figure 6, a limit switch 112 is supported by means of a bracket 113 beneath the square rod 32 with the operating button 114 of the switch contacting the underside of the rod. The arrangement is such that when the rod is pulled outwardly to its fullest extent, the operating button clears the left-hand end of the rod 32 and thus is free to move upwardly. When the rod is returned, it engages the button and depresses it to the position shown in Figure 6. Similar switches are similarly associated with each of the remaining rods 56, 57, 58 and 59. As hereinafter more fully pointed out, each of these switches controls two separate circuits and closes both circuits when the associated rod is fully out. The switch 112 and the corresponding switches 115, 116, 117 and 118 for the remaining square rods are illustrated diagrammatically in Figure 9.

The second set of switches comprises switches 119, 120, 121, 122 and 123, which are so associated, respectively, with the screws 12 to 16 that they remain closed as long as any article is supported on the screw with which they are associated, but open when the last article is discharged from that screw. Thus, the switch 119 comprises a flexible leaf spring 124 which is mounted at one end on a rod 125 carried by the housing 7 and

which carries at its opposite end a switch contact 126 which is adapted to co-operate with a contact 127 carried by an arm 128, which is also mounted on the rod 125. The underside of the leaf spring 124 bears lightly on the upper edge of the envelope which is supported on the outer extremity of the screw 12 and is held by the envelope in its uppermost position, in which the contact 126 remains in engagement with the contact 127. As soon as the last envelope is discharged from the screw, the leaf spring 124 is permitted to deflect downwardly and thus open the contacts. The remaining switches 120, 121, 122 and 123 are similar in construction and mode of operation and are illustrated diagrammatically in Figure 9.

As shown in Figure 8, the coin mechanism includes a coin deposit opening 129 adapted to receive coins of the appropriate denomination. Coins deposited in the slot 129 enter a slug rejector 130, which may be of conventional construction and which serves to separate bogus or defective coins from genuine coins, the former being discharged into a chute 131 and the latter into a chute 132. Chute 131 communicates directly with a coin return pocket 133 accessible from the exterior of the machine. Legitimate coins discharged through chute 132 pass a pivoted switch operating arm 134, which is thus swung in a clockwise direction to momentarily close a contact between the arm and a stationary contact 135. The coins then pass downwardly and come to rest on the flat surface 136 formed on a member 137 which is pivoted by means of a pin 138 in such a position that the flat surface 136 closes the lower end of the chute 132. Thus, the coins deposited in the machine initially come to rest at the lower end of the chute 132 and in engagement with the surface 136. The member 137 is provided with a pair of coin chutes 139 and 140 which merge with a downwardly projecting chute 141 which, in the normal position of the parts illustrated in Figure 8, terminates above a relatively flat surface 142 which closes the lower end of the chute 141. A pair of solenoids 143 and 144 is pivoted by means of pins 145 and 146 to the casing and has its movable armatures connected by means of links 147 and 148 to opposite sides of the chute 141. Springs 149 and 150 normally urge the links 147 and 148 toward the chute 141, and thus serve to center the chute in the position illustrated. On energization of either of the solenoids 143 or 144, the pivoted element 137 is swung at its lower end toward the energized solenoid. Thus, on energization of solenoid 143, the element 137 is rotated in a clockwise direction, as viewed in Figure 8. This permits any coins which were resting on the surface 136 to pass downwardly through the chutes 139 and 141 into an auxiliary coin return chute 151 which communicates with the pocket 133. Energization of solenoid 144 swings the element 137 in the opposite direction and permits the coins to pass downwardly through chutes 140 and 141 into the reservoir 152.

As shown in Figure 9, the electrical circuit comprises a pair of electric supply lines 153 and 154. The switch 135 is connected in series with a relay coil 155 across the lines 153 and 154 and, accordingly, on the passage of a coin through chute 132, contact 135 will be momentarily closed and thus energize the relay coil 155. The relay 155 is provided with a holding circuit 156, including the normally open contact 157 of the relay 155, and, consequently, the relay 155 remains energized after switch 135 opens.

The contacts 158, 159, 160, 161 and 162, which comprise one of the two contacts in each of the switches 112, 115, 116, 117 and 118, are connected in parallel with each other and in series with the coil of a relay 163 across the lines 153 and 154. The switches 119, 121, 122 and 123 are connected, respectively, in series with the contacts 164, 165, 166, 167 and 168 by means of lines 169, 170, 171, 172 and 173, and the lines 169 to 173, inclusive, are connected in parallel with each other and in series with the coil of a relay 174 across the lines 153 and 154.

The relay 155 has a normally open contact 175 in a line 176 which contains the latch release 15 solenoid 79, as a result of which energization of the relay 155 effects release of the latches 67, 68, 65, 69 and 70. The relay 163 is provided with a holding circuit 177 containing a normally open contact 178 of the relay 163 and a normally open contact 179 of the relay 155. The relay 174 is provided with a holding circuit 179 containing a normally open contact 180 of the relay 174 and a normally open contact 181 of the relay 155. The main circuit of the relay 174 also contains a normally open contact 182 of the relay 155. The relay 163 is provided with a normally closed contact 183 in the main circuit of the relay 155 and a normally open contact 184 in the circuit of the coin return solenoid 143. The contacts 183 and 184 of relay 163 are of the delayed action type, being connected to the relay armature by a spring and associated with a one-way acting dashpot in the usual manner. Contact 183 is so arranged that its opening movement is delayed for a predetermined period after energization of relay 163, while contact 184 has a similar but shorter delayed closing period. Thus, for example, the dashpot mechanism may delay the closure of contact 184 for two to three seconds after the relay 163 is energized, and the dashpot associated with contact 183 may delay the opening of the contact for approximately six seconds after the relay is energized. Contact 183 will close and contact 184 will open immediately upon de-energization of the relay 163.

The relay 174 contains a normally closed contact 185 in the main circuit of the relay 163, a normally open contact 186 in the circuit of the coin deposit solenoid 144, and a normally open contact 187 in the circuit of the motor 46.

The operation of the mechanism is as follows. On deposit of a coin in slot 129, switch 135 will be closed momentarily, thus energizing relay 155, and the coin will come to rest on the flat surface 136 of the element 137. Energization of relay 155 closes contact 175 and thereby energizes the latch release relay 179 and makes it possible for any selected one of the pull knobs 60, 61, 34, 62 and 63 to be pulled outwardly. Thereupon, the operator will pull a selected knob. When the selected knob is pulled outwardly to its fullest extent, one of the limit switches 112, 115, 116, 117 or 118 will close, at least momentarily. If the screw associated with the knob which is carrying one or more articles, the corresponding switch of the group consisting of switches 119 to 123, inclusive, will be closed and, therefore, both of the relays 163 and 174 will be simultaneously energized. Energization of relay 174 immediately opens contact 135 and thus de-energizes relay 163 before the delayed closing contact 184 of relay 163 can close. Therefore, the coin return solenoid 143 will not be energized. On the contrary, relay 174 will close contact 186 and thus energize 70 the coin deposit relay 144 and at the same time

the relay 174 will establish a holding circuit for itself by closing contact 180. The coin deposit relay 144 will remain energized until the circuits through relay 174 are broken by the opening of contacts 181 and 182 of relay 155. This will occur as soon as the delayed opening relay contact 183 of relay 163 opens the circuit through relay 155. In the meantime, the contact 187 of relay 174 will have closed on energization of the relay 174 and started the motor 46. The period of delay in the opening of contact 183 is made sufficient to insure not only complete operation of the coin deposit solenoid 144, but a sufficient period of operation of the motor 46 to completely discharge an article released from the rearmost supporting screw 16. As soon as this period has been completed, the opening of contact 183 will de-energize relay 155 and return all portions of the electrical circuit to the position shown in the drawings. It is desirable to de-energize the latch solenoid 79 as soon as the control knob is pulled out to its fullest extent. Accordingly, there is provided in connection with the relay 174 a normally closed contact 188 in the circuit of the solenoid 79 which will open and de-energize the solenoid 79 as soon as one of the knobs is pulled outwardly.

In the event that the screw corresponding to the selected knob is carrying no articles, the corresponding switch of the group 119 to 123 will be open and, consequently, relay 174 will not be energized when the knob is pulled fully out. This prevents operation of the coin deposit solenoid 144. Nevertheless, the relay 163 will be energized, thus closing contact 184 after a short delay and energizing the coin return solenoid 143. This returns the deposited coin to the coin return pocket 133.

While only one preferred form of the invention is illustrated and described herein, it will be apparent that variations in the design and arrangement may be indulged in without departing from the spirit of the invention or the scope of the appended claims. In this connection, an important feature of the invention resides in the use of cantilever mounted supporting and feeding screws for the articles dispensed by the machine. Such screws are of peculiar utility for use in dispensing articles such as phonograph records in paper envelopes, and it will be apparent that the advantages of such a construction may be realized regardless of the nature of the mechanism utilized to rotate the screws in a step-by-step manner. Thus, other forms of manually operated mechanisms may be employed or the screws may be rotated by one or more electric motors, if desired.

What is claimed is:

1. In a coin controlled dispensing machine for dispensing any one of a plurality of types of articles, a plurality of article discharging members mounted for reciprocation in parallel paths, manually operated means accessible on the exterior of said casing for reciprocating each of said members, each of said members having a notch formed therein, and a locking plate pivoted in said casing on an axis parallel to the direction of movement of said members and having its periphery extending into the notches in said members, the periphery of said plate having a plurality of notches so spaced as to permit reciprocation of only one of said members at a time.

2. In a coin controlled dispensing machine for dispensing any one of a plurality of types of articles, a plurality of article discharging members

mounted for reciprocation in parallel paths, manually operated means accessible on the exterior of said casing for reciprocating each of said members, each of said members having a notch formed therein, and a locking plate pivoted in said casing on an axis parallel to the direction of movement of said members and having its periphery extending into the notches in said members, the periphery of said plate having a plurality of notches so spaced as to permit reciprocation of only one of said members at a time, at least one set of said notches having beveled cam edges whereby upon movement of any one member the plate will be swung to align the notch therein with said member and to move the remaining notches in said plate out of alignment with the remaining members.

3. In a coin controlled dispensing machine for dispensing any one of a plurality of types of articles, a plurality of article discharging members mounted for reciprocation in parallel paths, manually operated means accessible on the exterior of said casing for reciprocating each of said members, each of said members having a notch formed therein, a locking plate pivoted in said casing on an axis parallel to the direction of movement of said members and having its periphery extending into the notches in said members, the periphery of said plate having a plurality of notches so spaced as to permit reciprocation of only one of said members at a time, means normally acting to prevent reciprocation of all of said members, and coin controlled means for rendering said last mentioned means inoperative until one of said members has been moved.

35 4. In a coin controlled dispensing machine for dispensing any one of a plurality of types of articles, a plurality of article discharging members mounted for reciprocation in parallel paths, manually operated means accessible on the exterior of said casing for reciprocating each of said members, each of said members having a notch formed therein, a locking plate pivoted in said casing on an axis parallel to the direction of movement of said members and having its periphery extending into the notches in said members, the periphery of said plate having a plurality of notches so spaced as to permit reciprocation of only one of said members at a time, at least one set of said notches having beveled cam edges whereby upon movement of any one member the plate will be swung to align the notch therein with said member and to move the remaining notches in said plate out of alignment with the remaining members, means normally 40 acting to prevent reciprocation of all of said members, and coin controlled means for rendering said last mentioned means inoperative until one of said members has been moved.
